UNITED STATES PATENT OFFICE

ROY E. PETERSON, OF EAST NORWALK, CONNECTICUT, ASSIGNOR TO THE E. H. HOTCHKISS COMPANY, OF NORWALK, CONNECTICUT, A CORPORATION OF CONNECTICUT

STAPLING MACHINE

Application filed June 12, 1929. Serial No. 370,341.

This invention relates to stapling machines and more particularly to improved means for feeding and clinching the staples, and has for an object to provide a clinching means for 5 stapling machines which will so clinch the staple that it will lie flat against the surface of the work, thus overcoming the objections to the manner in which the staples are set by the ordinary stationary curved anvil which 10 leaves the staples curved so that they project an undesirable distance above the face of the work.

It is a further object of the invention to provide a stapling machine in which a magnetic feeding means is substituted for the conventional spring feeding means. With the foregoing and other objects in view this invention consists in certain novel features of construction, combinations and arrangements 20 of parts as will be more fully disclosed in the accompanying drawings.

In the drawings

Fig. 1 is a side elevation of a stapling machine provided with my improved construction.

Fig. 2 is a front elevation thereof.

Fig. 3 is a vertical section on the line 3—3 of Fig. 1.

Figs. 4 and 5 are side and end elevations 30 respectively showing the anvils.

The machine comprises the usual base 12 to which is pivoted the housing 13, of non-magnetic material such for example brass or white metal, at 14 carrying the vertical reciprocable plunger 15 for driving the individual staple 16. In the present machine these are wire staples either round or more or less flat and fed on the non-magnetic guide bar 17 and are fed beneath the plunger 15 to operative position by a horse shoe or other suitably shaped magnet 18 which is held in proper place by any suitable means as a screw 19 in the housing 13. The poles 18' of the magnet are arranged on the opposite side of 40 the plunger 15 from the staple guide bar 17 and preferably in line with the prongs 16' of the staples on this bar as shown. The plunger 15 is operated by the hand knob 20 and is held in the upper position by spring 21 either 45 inside or outside of the housing as desired.

It will, of course, be understood that when the plunger is depressed it carries down the forward staple and drives it through articles to be stapled such as sheets of paper 22, placed under the housing and on top of the anvil. 55 The staples are usually of magnetic material such as iron wire and so they will be drawn forwardly to place the successive staples in position under the plunger, the magnet will hold the last staple or any loose staple in position under the plunger and prevent its dropping down or out the plunger guide way. This feed does away with the complicated staple feeds using springs and movable elements. 60

My improved anvil construction is mounted in a block 23 carried by the base 12 under the forward end of the housing. This block has a transverse slot in which are mounted the slideable anvils or staple clinching 70 means. In Figs. 2 and 3 there are two anvils 24 each slidably guided in the block by the pin 25 and slot 26. Mounted below the base is a resilient plate 27 which is secured at its rear end at the under side of the base by any suitable means. This plate is curved so that at its forward end it is normally spaced from the lower surface of the base, as shown in Figs. 1 and 2. In other words the base is supported a suitable distance above this plate and the forward ends of the housing and plate are moved relatively to each other. Coil springs 29 may also be placed between this base and this plate to assist the plate supporting the base but permit the relative movement between the two. Carried by the base plate 27 is an upright block 30 which is beveled at its upper edge to form cam surfaces 31 on which the slideable anvils 24 rest and have their cam surfaces 32 in contact therewith. Recesses 33 in the anvils 24 provide pockets for receiving the ends of the spring 35 which tends to urge the anvils 24 apart to the limit of their pin and slot connections. 85

When the machine is not operating the elements are in the position of Fig. 2. If now, it is desired to staple sheets of papers 22 for instance, the forward end of the housing is raised and the paper is inserted beneath the 100

housing on top of the block 23. If now, a blow of the hand is struck on the knob 20 the plunger 15 is depressed forcing the prongs of the forward staple which has been fed beneath the plunger by the attraction of the magnet 16 through the work, it being understood that the staple is of substantially inverted U-shape with the prongs depending from the body. Continued movement of the plunger downwardly forces the forward end of the base 12 and the block 23 carrying the anvils 24 downwardly toward the plate 27 and the upright cam member 30 because downward movement of the plunger relative to the housing is limited by any suitable conventional means, such as a shoulder 37 on the plunger engaging a stop 38 in the housing. This causes the cam surfaces 31 of the member 30 to push upwardly on the lower cam sides 32 of the anvils 24 and slide them along their pin and slot connection to the position of Fig. 3. While they slide to this position the anvils engage the prongs of the staple and fold them against the under side of the work, as shown in Fig. 3. When the machine is in the position of rest these anvils are separated or urged apart to the limits of their pin and slot connections as shown in Fig. 2. It is preferred also that the upper edges of these anvils be grooved, as shown at 36, to better hold the staples in proper position. It will be seen from this operation that the prongs of the clinched staples shown at 16' Fig. 3, are pressed flat against the under side of the work and are not left curved as is the ordinary operation of the machine using a stationary anvil, because the stationary anvil in order to properly bend the prongs must have curved bending surfaces and they, therefore, leave the prongs curved so that they project in an undesirable amount above the surface of the work. With this present construction, however, the prongs are laid perfectly flat giving a much better clinching effect, and as the staple does not project far from the surface of the work it is much less liable to catch on other objects.

Having thus set forth the nature of my invention, what I claim is:

50 1. In a stapling machine, a base, a housing pivoted to the base, a reciprocable plunger carried by the housing, an anvil carried by the base and slidable to force the free end of a staple toward the under side of the articles to be stapled, means below the base on which the base rests and movable toward the base, means carried by the latter means to slide said anvil laterally on depression of the plunger and spring means to normally hold the base above the carrier for the anvil operating means.

60 2. In a stapling machine, a base, a housing pivoted to the base, a reciprocable plunger carried by the housing, slidable anvils carried by the base, yieldable means urging said

anvils away from each other, means below the base on which the base rests movable toward the base, cam means on the latter means for sliding said anvils toward each other on movement of said plunger, and spring means tending to separate the base and said latter means.

3. In a stapling machine, a base, a housing hinged to the base, a vertically reciprocable plunger carried by the housing, means in said housing to feed staples to said plunger, a transversely reciprocable anvil below the plunger and operable in a direction at right angles to the direction of movement of the plunger and adapted to cooperate therewith to set the staples, and means operated by downward movement of the housing for operating the anvil.

4. In a stapling machine, a base, a housing hinged to the base, a vertically reciprocable plunger carried by the housing, means in said housing to feed staples to said plunger, a pair of anvils carried by the base below the plunger and slidable toward and from each other in a direction substantially at right angles to the direction of movement of the plunger, and adapted to cooperate therewith to set a staple, and means below the base and movable to cam the anvils toward each other.

5. In a stapling machine, a base, a housing hinged to the base, a vertically reciprocable plunger carried by the housing, a pair of anvils carried by the base below the plunger and slidable toward and from each other and adapted to cooperate with the plunger to set a staple, means below the base and movable to cam the anvils toward each other, and yieldable means urging said anvils apart.

6. In a stapling machine, a base, a housing hinged to the base, a vertically reciprocable plunger carried by the housing, a pair of sliding anvils carried by the base below the plunger, a subbase below the said base normally spaced therefrom and movable toward it, and a cam carried by said subbase to actuate the anvils toward each other.

7. In a stapling machine, a base, a housing pivoted to the base, a reciprocable plunger carried by the housing, a pair of reciprocable sliding anvils carried by the base under the plunger and adapted to reciprocate in timed relation therewith to fold the ends of a staple against the under side of the work, and means below the base movable toward the same having means adapted by said movement to actuate the anvils toward each other into cooperation with the plunger.

8. In a stapling machine, a base, a housing hinged to the base, a vertically reciprocable plunger carried by the housing, a plurality of anvils, each of said anvils having a staple clinching surface thereon, pin and slot guide means for each anvil, yieldable means urging said anvils apart, cam surfaces

on said anvils, a subbase normally spaced below the first base and movable toward it, and a cam carried by the subbase in contact with the cam surfaces of said anvils to actuate the anvils into cooperation with each other and with the plunger.

9. In a stapling machine, a base, a non-magnetic housing pivoted to the base, a non-magnetic staple guide bar carried by the housing, a reciprocable plunger carried by the housing, magnetic staple feed means carried by said housing, an anvil slidably guided by said base for cooperation with said plunger to set a staple, a subbase below the base, and a cam on said subbase in contact with said anvil to actuate the same on depression of the plunger.

In testimony whereof I affix my signature.
ROY E. PETERSON.
